TUNING CONTROL MECHANISM

William T. Cooke, Huntington, and Kenneth L. Schussman, Hempstead, N. Y., assignors to Sperry Gyroscope Company, Inc., Brooklyn, N. Y., a corporation of New York

Application October 7, 1941, Serial No. 413,982

25 Claims. (Cl. 250—27.5)

This invention relates to an improvement in tuning control mechanisms particularly adapted for use with a high frequency tube structure having cavity resonators of the general type disclosed in application Serial No. 342,912, filed June 28, 1940, by William T. Cooke, Joe J. Caldwell, Jr., and David G. Clifford.

The primary features of the present invention reside in the structural provision of a novel mechanism by which either cooperative or independent tuning of the respective resonators of a high frequency tube structure of the character such as disclosed in the aforementioned application for Letters Patent may be effected.

Other features and advantages will become apparent from the specification when read in connection with the accompanying drawings, wherein

Fig. 1 is a longitudinal elevation view, partly in section, showing the tube structure with the improved tuning mechanism mounted thereon.

Fig. 1A is a fragmentary side elevation partly in section illustrating the resonator trimming control of the invention.

Fig. 2 is an end view of the tube structure shown in Fig. 1.

Fig. 3 is a detail cross section of a modified form of the tuning control mechanism illustrated in Fig. 1, and

Fig. 4 is a view similar to Fig. 1, also partly in section, illustrating a further modified form of the improved tuning mechanism by means of which individual resonators of the tube structure are controlled.

With particular reference to Figs. 1 and 2, showing the preferred form of the invention, the improved control mechanism is mounted on a high frequency tube structure of the type disclosed in the heretofore identified application for Letters Patent. In the present instance, however, the detector construction shown in the left-hand end of the tube structure in the noted application has been omitted. This conventional tube structure includes adjoining resonator chambers 1 and 2 having oppositely disposed parallel flexible diaphragms designated at 3 and 4, control over whose deflection is obtained by the improved mechanism. The detailed construction of the flexible and fixed wall resonating chambers of the tube structure of this character is clearly shown in Fig. 1 of the aforementioned application for Letters Patent.

The mounting pieces for the improved mechanism include a flange element 6 which is centrally located with respect to the resonator chambers

1 and 2 and surrounds the same. On the cathode end of the tube is situated a similar flange element designated at 7 and located in parallel relation to flange 6. Also, on the opposite end of the tube and situated in similar relationship is a further flange designated at 5. Flanges 5 and 7 are preferably positioned at the same spaced distance along the tube from the centrally located fixed flange 6. The improved control mechanism is mounted on the tube by means of the respectively noted flanges which extend from the body of the evacuated tube structure. Abutting clamp rings 13 and 14 which fit over flanges 5 and 7 are of similar construction and are held in position thereon in both instances by suitable means, such as a number of screw fastening connections for the parts as designated at 14'. The clamped rings 13 and 14 on both flanges 5 and 7 having threaded openings therein which are adapted to receive adjustable screw elements 15 to 20 inclusive. Screw elements 15, 16, 17 are employed with the clamping rings mounted on flange 5 and elements 18, 19 and 20 are used on the similar clamping rings fixed to flange 7. The respective screw elements being three in number for each of the clamped rings are arranged at 120° spaced intervals around the periphery of the respective rings as clearly illustrated in the case of screw elements 18, 19 and 20 in Fig. 2.

The ends of the respective adjusting screw elements 15 to 20 disposed towards the central flange 6 are shaped to provide a mounting for jacks or connecting thrust pieces, only four of which are illustrated in the drawing, the same being designated at 8, 9, 10 and 11. In Fig. 1, the associated parts include jack 8-screw 16, jack 9-screw 19, jack 10-screw 15 and jack 11-screw 18. The respective adjusting screws 15 to 20 inclusive provide thrust bearings for the jacks or connections therewith and serve to provide a way in which an initial rough adjustment of the tuning of the resonators of the high frequency tube structure may be facilitated as particularly shown and described in Hausen et al. Patent No. 2,311,658, issued February 23, 1943. This portion of the improved mechanism provides the thrust structure by which the deflection of the flexible walls of the tube is effected.

After rough tuning of the device is accomplished by manual setting of the screws 15 to 20, inclusive, permanent gang tuning is provided by the presently described mechanism which controls only one pair of the three oppositely spaced pairs of tuning jacks and their respective con-

necting screws. In the instant case, the oppositely disposed pair of jacks 8 and 9 are controlled by the mechanism in effecting gang tuning of the tube as shown in Fig. 1. It will be understood that the tuning is effected by joint movement of the diaphragms 3 and 4, in this instance, through means of the respective jacks 8 and 9 with their associated screws 16 and 19 which control the degree of movement of the respective clamped rings. The rings in this event pivot about the stationary contact points of screws 15 and 18 and jacks 10 and 11, and screws 17 and 20 with the jacks associated therewith, the flanges 5 and 7 thereby being simultaneously urged in corresponding directions to exert the desired control over the flexible diaphragms or walls 3 and 4 of the tube.

The central clamping ring construction is shown by parts 29 and 30, part 29 corresponding in form to the previously designated ring elements 13 for flanges 5 and 7 and part 30 corresponding to the respective similar rings shown at 14. The rings are also similarly connected and mounted in position on the centrally disposed fixed flange 6. As shown in Fig. 1, a screw member 31 is situated on the ring clamps 30 and 29 and located between the respective fixed position jacks 10 and 11. The housing construction for the tuner control mechanism, in this instance, is provided on the clamp ring 29 and is shown in the form of two hollow tubular casing members extending tangentially from the ring as designated at 32 and 32', the same also preferably being situated in parallel relation to one another. A suitably fixed centrally positioned wall 21 is located within each of the casing interiors, the wall terminating in an extended screw threaded portion designated at 22. A longitudinally movable knob 24 is rotatably mounted on the screw threaded extension 22 and includes an interiorly disposed tapered or conical body piece 23. In the embodiment of the invention shown in Fig. 1, oppositely situated lever arms 25 and 26 are pivoted within the casing 32 as designated at 33. A portion and preferably the opposite end of the respective arms 25 and 26 engages the tapering or conical wedge-shaped surface of the knob body piece 23. Openings are provided in the tubular casing 32 through which the jacks 8 and 9 slidably extend, the ends of the jacks being located in seat forming portions provided on the surface of the respective levers 25 and 26. By rotating the knob 24 of the gang tuner in a desired direction the position of the conical body 23 is varied which effects simultaneous movement of the lever arms 25 and 26 and thus influences and positions the respective movable jacks 8 and 9 to control the setting of the flexible diaphragms 3 and 4 as previously described. By distorting flexible diaphragms 3 and 4, the distance between the resonator grids contained within the respective chambers 1 and 2 is altered thus changing the resonant frequencies of the same as particularly disclosed in the second aforementioned application for Letters Patent. It will be understood that for gang tuning both resonators are controlled in the same frequency change sense by means of knob 24.

For trimming or matching the frequencies of the respective resonators, the knob 24' is employed, as illustrated in Fig. 1A. The construction of the control mechanism actuated by knob 24' is similar to that heretofore described except for the fact that only one lever 26 is used and consequently only one of the associated movable jacks 9 with the same. This control mechanism

is further adapted to usually exert its influence upon the buncher resonator of the tube structure. In this arrangement jack 8' opposite the one whose position is determined by the matching control mechanism may bear directly against the side surface of the internally located central wall 21.

10 A mounting flange 35 may be situated on the casing structure 32 and 32' by means of which with a suitable connecting piece the tube structure may be fixed in position on an apertured plate 36.

15 Fig. 3 shows a modification of the construction illustrated in Fig. 1 in which cantilevers 40 and 41, the ends of which are mounted in a fixed base piece 42, take the place of the pivotally mounted lever arms 25 and 26. The opposite ends of the cantilever arms 40 and 41 are positioned against the body of the wedge piece 23 on the knob 24 and the same is further constructed to cooperate with jacks 8 and 9 as heretofore described.

20 A further modified form of the invention is shown in Fig. 4, in which a separate tuner or improved control mechanism is employed with each 25 of the resonator chambers of the tube. In this construction, the resonant frequency of the tube structure in chamber 2 is altered by changing the distance between the grids 46 and 47 through 30 means of manual adjustment of a turnable knob 48. The internally screw threaded knob 48 is provided with a tapering or wedge body surface 49 similar to that described in connection with the illustrated form of the invention shown in Fig. 1, the tapered surface however, in this instance, sloping toward the knob 48 instead of in the opposite direction. Knob 48 is longitudinally 35 adjustable along screw piece 50 which is suitably mounted in a fixed position on the grid supporting tube 60 extending from diaphragm 45. A 40 lever arm 51 is pivotally mounted at 52 on a supporting plate 53, fixed to the outer rigid wall of chamber 2, includes a roller bearing member 54 at one end of the same through means of which cooperation with the tapered thrust surface 49 is 45 obtained. An extending arm 55 of the lever 51 engages the face of an annular ring or thrust member 56 which is positioned tightly against the central portion of plate 53 on the screw 50. Consequently, the position of grid 46 with respect to 50 grid 47 is controlled by the manual setting of knob 48, the outward movement being imparted to grid 46 by means of lever arm 51 and thrust member 56 which is axially movable with the central portion of plate 53 and diaphragm 45 as one 55 piece, the inward movement of grid 46 being augmented by the natural resilience of the diaphragm 45 and the pressure of the atmosphere thereon. In this instance, the screw element 50 also forms 60 a portion of the movable parts on which grid 46 is mounted as the same is fixed thereto in a suitable manner.

65 As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

70 What is claimed is:

1. A tuning control mechanism connected to a high frequency tube structure having a cavity resonator with rigid and flexible wall portions, comprising a longitudinally movable tapered member, 75 a lever having a portion engaging the tapered

member, and a thrust member interposed between the lever and the flexible wall whereby the deflection of the flexible wall is controlled by the longitudinal movement of said tapered member.

2. A mechanism as in claim 1, wherein said lever is pivotally connected to said rigid wall portion.

3. A mechanism as in claim 1, wherein said lever has one end fixedly connected to said rigid wall portion, whereby said lever serves as a cantilever.

4. A tuning control mechanism for a high frequency tube structure having a cavity resonator with a fixed wall portion and a movable wall portion, said mechanism comprising a support adapted to be fixed to one of said wall portions, a tapered member mounted on said support for longitudinal movement, a pivoted lever having a portion engaging said tapered member, and a thrust member adapted to be interposed between said lever and the other of said wall portions, whereby relative movement between said wall portions may be controlled by the longitudinal movement of said tapered member.

5. A tuning control mechanism connected to a high frequency tube structure having a cavity resonator with rigid and flexible wall portions, comprising a rotatably mounted member having a conically shaped portion thereon longitudinally movable on rotation of the member, a lever having one end of the same contacting to the conically shaped portion of the rotatable member, and a thrust connection between said lever and flexible wall whereby deflection of the flexible wall is effected by the turning of said member.

6. A tuning control mechanism connected to a high frequency tube structure having cavity resonators with rigid and a plurality of flexible wall portions, comprising a rotatably mounted member having a conically shaped portion thereon longitudinally movable on rotation of the member, a plurality of levers each of which has a portion contacting the peripheral surface of the conically shaped portion of the rotatable member, and a thrust connection between each of said levers and one of the flexible walls of the tube whereby deflection of said flexible wall is effected by the turning of said member.

7. A tuning control mechanism connected to a high frequency tube structure having a cavity resonator with rigid and flexible wall portions, comprising a longitudinally movable tapered member, a pivotally mounted lever having a free portion engaging the tapered member, and a thrust member interposed between the lever and the flexible wall whereby the deflection of the flexible wall is controlled by the longitudinal movement of said tapered member.

8. A tuning control mechanism connected to a high frequency tube structure having a cavity resonator with rigid and flexible wall portions, comprising a longitudinally movable tapered member, a cantilever having one of its ends engaging the tapered member, and a thrust connection between said cantilever and flexible wall whereby deflection of the flexible wall is effected by the movement of said member.

9. A tuning control mechanism connected to a high frequency tube structure having a cavity resonator with rigid and flexible wall portions, comprising a rotatably mounted member having a conically shaped portion thereon longitudinally movable on rotation of the member, a pivotally mounted lever having a portion contacting the peripheral surface of the conically shaped portion of the rotatably mounted member, and a thrust ring between the flexible wall and the lever where-

by deflection of the flexible wall is effected by the turning of said member.

10. A tuning control mechanism connected to a high frequency tube structure having a cavity resonator with a flexible wall portion, comprising a longitudinally movable tapered member, lever means actuated by said tapered member, and force transmitting means interposed between the lever means and the flexible wall portion of the cavity resonator whereby deflection of the flexible wall is controlled by the longitudinal movement of said tapered member.

11. A tuning control mechanism connected to a high frequency tube structure having a cavity resonator with a flexible wall portion, comprising a longitudinally movable tapered member, a cantilever actuated by said tapered member, and force transmitting means interposed between the cantilever and the flexible wall portion of the cavity resonator whereby deflection of the flexible wall is controlled by the longitudinal movement of said tapered member.

12. A tuning control mechanism connected to a high frequency tube structure having a cavity resonator with a movable wall portion, comprising a movable tapered member, a second member actuated by the taper of said tapered member upon motion of said tapered member, and force transmitting means interposed between said second member and said movable wall portion whereby the deflection of said movable wall is controlled by the movement of said tapered member.

13. A tuning control mechanism connected to a high frequency tube structure having a cavity resonator with a flexible wall portion, comprising a movable tapered member, a cantilever actuated by said tapered member, and force transmitting means interposed between said cantilever and said flexible wall portion whereby deflection of said flexible wall is controlled by the movement of said tapered member.

14. A tuning control mechanism connected to a high frequency tube structure having a cavity resonator with a flexible wall portion, comprising a movable tapered member, a second member actuated by said tapered member, and force transmitting means interposed between said second member and said flexible wall portion whereby deflection of said flexible wall is controlled by the movement of said tapered member.

15. Ultra high frequency apparatus comprising means defining a cavity resonator, spaced electrodes mounted in said resonator for relative separational tuning adjustment of said resonator, members rigid with each of said electrodes, a lever pivotally connected to one of said members and operably connected to the other of said members, a longitudinally shiftable device having a cam surface engaging said lever, and means for longitudinally displacing said device for controllably tuning said resonator.

16. Ultra high frequency apparatus comprising means defining a pair of cavity resonators, support means adjacent said resonators, shiftable tuning members connected to the respective resonators, a pair of cantilevers fixed at one end to said support means, force transmitting means engaged between each lever and a corresponding said support means, force transmitting means engaging both of said levers for gang tuning said resonators.

17. Ultra high frequency apparatus comprising means defining a pair of cavity resonators, support means adjacent said resonators, shiftable tuning members connected to the respective res-

onators, a pair of levers mounted on said support means, force transmitting means engaged between each lever and a corresponding tuning member, and a shiftable cam member engaging both said levers for gang tuning said resonators.

18. Apparatus as in claim 17, wherein said levers pivoted to said support means.

19. Apparatus as in claim 17 wherein said levers are cantilevers fixed at one end to said support means.

20. Apparatus as in claim 17, wherein said tuning members have means for adjusting the same, whereby individual tuning of said resonators may be effected independently of said gang tuning.

21. Ultra high frequency apparatus comprising means defining a cavity resonator, a shiftable tuning member engaging said resonator, a tuning control member displaceable substantially longitudinally of the resonator axis, and motion transmitting means interconnecting said members comprising a cam surface on said control member and a lever engaging said cam surface and extending between said cam surface and said tuning member.

22. Ultra high frequency apparatus comprising means defining a cavity resonator having a rigid wall portion and a movable wall portion, a shiftable tuning member engaging said movable wall portion, a shiftable cam member, a lever engaged by said cam member and pivoted on said rigid wall portion, and a motion transmitting connection between said lever and said tuning member.

23. Ultra high frequency apparatus embodying means defining a hollow resonator having a pair of spaced electrodes mounted for separational tuning adjustment, a tuning member rigid with one of said electrodes, a lever pivotally connected to the other of said electrodes and operably connected to said tuning member, and tuning control means comprising a shiftable cam engaging said lever.

24. High frequency apparatus comprising a hollow resonator having a wall portion movable in a predetermined direction and means for tuning said resonator comprising a movable tuning control member supported in said apparatus, means providing a cam surface on said member, and force transmitting means interposed between said surface and said wall portion.

25. High frequency apparatus comprising a hollow resonator having a wall portion movable in a predetermined direction and means for tuning said resonator comprising a tuning control member supported for motion in a direction substantially parallel to said predetermined direction and having a cam surface with portions at differing distances from said wall portion, and force transmitting means engaging said surface and said wall portion.

Patent No. 2,380,946.

CERTIFICATE OF CORRECTION.

August 7, 1945.

WILLIAM T. COOKE, ET AL.

It is hereby certified that error appears in the printed specification of the above numbered patent requiring correction as follows: Page 1, second column, line 45, for "Hausen" read --Hansen--; page 3, first column, line 29, claim 5, after the word "contacting" strike out "to"; and second column, line 69, claim 16, for "said support means, force transmitting means" read --turning member, and a shiftable cam member--; line 67, same claim, for "suport" read --support--; page 4, first column, line 7, claim 18, before "pivoted" insert --are--; and that the said Letters Patent should be read with this correction therein that the same may conform to the record of the case in the Patent Office.

Signed and sealed this 18th day of December, A. D. 1945.
